(57) **CLAIM**

The ornamental design for a trolley bag as shown and described.

DESCRIPTION

FIG. 1 is a top, front and left side perspective view of a trolley bag showing my new design;

FIG. 2 is a bottom, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dotted lines shown on the trolley bag depict stitching that form no part of the claimed design. The evenly dashed broken lines depict portions of the trolley bag that form no part of the claimed design.

1 Claim, 8 Drawing Sheets
